NECKTIE

Emilio E. Vecchi, Des Moines, Iowa

Application April 11, 1938, Serial No. 201,333

2 Claims. (Cl. 2—146)

The principal object of my invention is to provide a necktie that is highly durable in use, refined in appearance, and economical in manufacture.

A still further object of my invention is to provide a necktie that holds its shape even after long usage.

A still further object of this invention is to provide a necktie that ties into an attractive knot and does not wrinkle.

A still further object of my invention is to provide a necktie construction that produces a necktie that is braced, strengthened and padded in all directions of pull.

These and other objects will be apparent to those skilled in the art.

My invention consists in the construction, arrangement and combination of the various parts of the device, whereby the objects contemplated are attained as hereinafter more fully set forth, pointed out in my claims, and illustrated in the accompanying drawing, in which:

Fig. 1 is a top plan view of my necktie before the outer decorative covering has been folded and stitched in place.

Fig. 2 is a cross sectional view of my necktie taken on line 2—2 of Fig. 1 and more fully illustrates its construction.

Fig. 3 is a cross sectional view of my finished necktie ready for use.

Neckties have been used universally for many years but the main difficulties experienced by the users are that the ties do not hold their shape, wrinkle and become distorted by usage. I have overcome such objections by providing a necktie that is strong and durable and because of its construction has attractive rolled edges.

Referring to the drawing, I have used the numerical 10 to designate the elongated core, ribbon or strip. This strip 10 gives the body to the tie and may be considered as the basic piece of the tie. It should be of suitable fabric having both body and strength such as mohair or like. As is well known, many garments and coats use such material for strengthening, padding and like. In the manufacturer of my tie, directly below this elongated strip 10 I placed an elongated strip of cloth 11. This strip 11 may be of muslin or other suitable cloth material. As will be noted, the strip 11 is wider and longer than the strip 10 and the strip 11 is placed along the center of the strip 10 as shown in Fig. 1. Directly below the strip 11 is the decorative tie cover 12. Obviously this outer covering 12 is of silk or other appropriate attractive color and design. 55

The outer decorative cover 12 is wider and longer than the strip 11. The strip 11 is placed along the center line of the decorative covering 12. After the strips 10, 11, 12 are so placed as shown in Fig. 1, the edges of the strip 10 are secured to the covering 12 by stitching. As the strip 11 is between the strip 10 and outer covering 12, the strip 11 will also be rigidly secured some distance from its side edges to the covering 12 as shown in Fig. 2. Any type of stitch may be used but it is recommended that the stitching not completely extend through the front of the covering 12 as its appearance on the face of the tie would be objectionable. This stitching is shown in Fig. 2 and I have designated it by the numeral 13. After the tie has been so arranged and sewed, it is folded at the side edges of the strip 10 thus bringing the two side edge portions of the strip 11 over and over-lapping the side edge portions of the strip 10. The dimensions of the strips are so formed that this folding of the tie will bring the two side edges of the outer covering 12 into over-lapping construction as shown in Fig. 3. These over-lapping side edges 25 of the covering 12 are sewed together by thread or like 14 in the usual manner. By this construction the strip 10, the strip 11 and outer covering 12 are rigidly secured together at the marginal side edges of the strip 10, thereby providing a stable and well constructed necktie. 30 Due to the padding effect and strengthening characteristics it will be substantially wrinkle-proof. By the outer covering and the strip 11 encircling and embracing the side edges of the stiffening and strip core, strip 10, the finished tie 35 will have attractive rolled side edges.

From the foregoing it will readily be seen that I have provided a highly desirable necktie.

Some changes may be made in the construction and arrangement of my improved means for a necktie without departing from the real spirit and purpose of my invention, and it is my intention to cover by my claims, any modified forms of structure or use of mechanical equivalents which may be reasonably included within their scope.

I claim:

50 1. In a necktie, a center strip of strengthening material, an intermediate strip of flexible material having a width greater than the width of said center strip with its side marginal edge portions folded around said center strip and with its marginal side edges terminating in substantially

the same plane and spaced a substantial distance apart, and a unitary seamed decorative cover embracing said center and said intermediate strip with its seam disposed between the spaced apart marginal edges of said intermediate strip; the space between the marginal edges of said intermediate strip accommodating the overlapping edges of said unitary outer decorative covering at its seamed line.

2. In a necktie, a center strip of strengthening material, an intermediate strip of flexible material having a width greater than the width of said center strip with its side marginal edge por-

5 tions folded around said center strip and with its marginal side edges terminating in substantially the same plane and spaced a substantial distance apart, a unitary seamed decorative cover embracing said center and said intermediate strip with its seam disposed between the spaced apart marginal edges of said intermediate strip accommodating the overlapping edges of said unitary outer decorative covering at its seamed line, and stitching securing the said two strips and the decorative covering together at the outer side marginal edge of said center strip.

EMILIO E. VECCHI.
